Attorney.

UNITED STATES PATENT OFFICE

GEORGE D. OVERHOLTZ, OF LEETSDALE, PENNSYLVANIA, ASSIGNOR TO RITER-CONLEY MANUFACTURING COMPANY, OF PITTSBURGH, PENNSYLVANIA, A CORPORATION OF PENNSYLVANIA

ERCTION HANGER

Application filed July 3, 1929. Serial No. 375,812.

This invention relates to improvements in erection hangers designed for use in erecting structural steel members and the like, and it is especially applicable for use in the erection of steel frame panels employed in outdoor advertising structures.

In outdoor advertising structures, the steel frame panel sections are of considerable size and are awkward to handle, necessitating some means for temporarily holding said panels in place prior to and while the same are being bolted or riveted together and attached to the framing of the advertising structure.

15 It is a prime object of my invention to provide an erection hanger comprising work-engaging means, means for retaining the hanger on the work, and means for attaching the hanger on the supporting structure.

20 In the following specification and in the accompanying drawings, I have shown my invention in connection with an outdoor advertising structure but, as above stated, the erection hanger may be employed for other purposes.

Other objects are, to provide a hanger of the character specified which may be easily applied to panels and the like; a hanger which is economical to manufacture; and a 30 hanger which affords an efficient means for temporarily suspending panels on the framing for the purpose of securing them to other panels and to the framing.

Further objects and advantages will become apparent from the description taken in connection with the accompanying drawings, wherein:

Fig. 1 is a perspective view of an erection hanger embodying my invention; and

40 Fig. 2 is a perspective view showing the application of the hanger in erecting steel frame panels of an outdoor advertising structure.

Referring to the drawings, the hanger is 45 preferably formed of metal, and includes a bottom or base 2 provided with a depending hook portion 3. The angle between the base portion 2 and the hook portion 3 is slightly greater than a right angle, to permit the portion 3 to be easily engaged over the support-

ing framework of the structure being erected.

Projecting vertically from the base 2 is a guide member 4. This member extends upwardly and is provided with a vertically extending lever-receiving slot 5. 6 designates a side plate secured to the base 2 and guide member 4 in any suitable manner, as by welding. Said member is formed with an extension 7 projecting beyond the member 4, and carries a panel-engaging pin 8 which projects from extension 7 at right angles thereto.

Mounted at the opposite end of the side plate 6 by means of a rivet 9, I provide a locking or retaining lever 10 offset at 11 and extending through the slot 5 of the member 4. Lever 10 is formed with a handle portion 12 at its outer end.

In utilizing the hanger in the erection of steel frame panels of outdoor advertising structures, reference will be had to Fig. 2. 70 The panels A and A' are composed of side members a—a and end members b preferably formed of angle bars mitered and welded together, and a sheet or plate member 13 extending over said side and end members and bent thereon to secure the plate to the member.

The side members a—a are provided with spaced-apart openings 14 for securing adjacent panels together, and for securing the 80 panels to the supporting framework B. These panels are very long and heretofore have been difficult to handle, requiring a number of men to position the panel sections and to secure them to the framing.

85 The supporting framework B comprises uprights 15 and cross members 16, preferably formed of angle bars. Said members and uprights are secured together as by bolts 17. The framework is also provided with bracing members (not shown) to form a self-supporting unit.

In practice, a hanger is secured to each of the side members a—a of the first panel A. This is accomplished by removing locking 95 levers 10 from their slots 5, inserting panel-engaging pins 8 in the center openings 14 of said side members, as shown, and then replacing the levers 10 in their respective slots. Thus, it will be seen that the hangers are 100

temporarily secured to the panel, and the panel may be elevated until the hangers engage the middle cross member 16, being retained thereon by the depending portions 3.

5 When thus suspended, the locking lever 10 of the hanger on the inner side of the panel is removed from its slot 5, as shown in Fig. 2. A second panel A' having one hanger only is elevated until said hanger engages the cross member 16. Said panel may then be slid 10 along the cross member until the opening 14a engages the pin 8 of the hanger on the adjacent panel. Locking lever 10 may then be entered in its slot 5 and the adjacent sides 15 a—a of panels A and A' will be temporarily secured together in alignment. Additional panels may be erected in a similar manner.

Bent bolts or other suitable means may be employed in suspending the panels from the 20 cross members 16, replacing the hangers, and the panels are joined along their edges by rivets or bolts.

From the foregoing description, it will be understood that the panel sections may be 25 readily positioned on the framing and temporarily held in position with a minimum effort and expense.

Various changes and modifications are contemplated, provided they fall within the 30 scope of the following claims.

I claim:

1. An erection hanger including a base adapted to be positioned on a structural member support, said base provided with oppositely projecting end members, a side plate, a work-engaging pin on the side plate, and a pivotally mounted lever for retaining the hanger on the work operable in an end member.
2. An erection hanger including a base provided with oppositely projecting end members, a side plate, a pin on the side plate, and a pivotally mounted lever, one of the end members being slotted to receive said lever.
3. An erection hanger including a base provided with oppositely projecting end members, a side plate fixedly secured to an edge of the base and to an edge of one end member, a pin on the side plate, and a pivotally mounted lever.

In testimony whereof I affix my signature.

GEORGE D. OVERHOLTZ.
